DESIGN FOR A PRISM BINOCULAR

Andrew Wollensak and Gustav F. Pirwitz,
Rochester, N. Y., assignors to Wollensak Optical Company, Rochester, N. Y., a corporation of New York

Application January 16, 1936, Serial No. 60,629

Term of patent 14 years

To all whom it may concern:

Be it known that we, Andrew Wollensak and Gustav F. Pirwitz, both citizens of the United States of America and both residing at Rochester, in the county of Monroe and State of New York, have invented a new, original, and ornamental Design for a Prism Binocular, of which the following is a specification, reference being had to the accompanying drawings, forming a part thereof.

In the drawings:

Fig. 1 is a top plan view of a binocular showing our new design;

Fig. 2 is a side elevation;
Fig. 3 is a bottom plan view;
Fig. 4 is a side elevation looking in the opposite direction from Fig. 2;
Fig. 5 is an end elevation, and
Fig. 6 is an end elevation looking in the opposite direction from Fig. 5.

We claim:

The ornamental design for a prism binocular, as shown.

ANDREW WOLLENSAK.
GUSTAV F. PIRWITZ.
